UNITED STATES PATENT OFFICE.

EDWIN M. ROSENBLUTH, OF PHILADELPHIA, PENNSYLVANIA.

ACETYLENE-GAS GENERATOR.

1,173,122.

Specification of Letters Patent.

Patented Feb. 22, 1916.

Application filed September 18, 1913. Serial No. 790,395.

To all whom it may concern:

Be it known that I, EDWIN M. ROSENBLUTH, a citizen of the United States, residing at Philadelphia, in the county of Philadelphia and State of Pennsylvania, have invented a certain new and useful Improvement in Acetylene-Gas Generators, whereof the following is a specification, reference being had to the accompanying drawings.

10 My invention relates to a generator of the type described in Letters Patent of the United States 1,025,648 granted to me May 7, 1912, and provides such a generator with a carbid casing and appurtenances adapted 15 for coöperation with carbid cartridges which, as hereinafter described, include a flexible cover of textile fabric having a series of compartments independently charged with carbid so that the latter is 20 equally distributed throughout the length of the cartridge when the latter is extended in the plane position in which it is formed, and also when it is bent to the annular position which it occupies in the carbid casing.

25 As hereinafter described, my invention includes a generator so constructed that its base frame may be permanently attached to an automobile and the carbid casing and water receptacle be detachably rigidly connected therewith by rotation of a rod extending centrally through said water receptacle, in threaded engagement with a screw threaded stem extending through said carbid casing from said base; said stem extending through a condensate trap in said base and carrying at its lower end a closure for a vent opening in the bottom of said trap; said closure being spring pressed so 30 as to be automatically opened whenever said stem is released by rotation of said connecting rod. As hereinafter described, said water receptacle includes a main compartment adjacent the carbid chamber and an auxiliary compartment above said main compartment; and a water passageway leading from said main water compartment into the carbid casing is controlled by a rotary valve which also controls a gas passageway 35 leading from said carbid casing to the atmosphere, the construction and arrangement being such that when the gas passageway is opened the water passageway is closed and vice versa; said valve being rotatable by a rod extending from the main water compartment through the auxiliary

water compartment and having an operating handle exterior to the latter, and said rod carrying a valve controlling communication between said auxiliary compartment and said main compartment so as to place them in communication only when said water passageway leading from said main compartment to said carbid casing is closed. However, such means for automatically 65 draining the condensate from the generator is claimed in my copending application Serial 784,292, filed August 12, 1913, for Letters Patent of the United States, and said carbid cartridge and the means for compressing the same are claimed in my copending application Serial 790,396, filed Sept. 18, 1913.

The specific claims in this case are limited to the construction and arrangement 75 of the water feeding mechanism and my invention includes the various novel features of construction and arrangement herein-after more definitely specified.

In the drawings: Figure I is a plan view 80 of a generator conveniently embodying my invention. Fig. II is a vertical sectional view of said generator taken on the line II, II in Fig. I. Fig. III is a fragmentary sectional view on the same line as Fig. II 85 but showing a different position of the rotary valve. Fig. IV is a fragmentary horizontal sectional view taken on the line IV in Fig. II. Fig. V is a fragmentary horizontal sectional view taken on the line V 90 in Fig. II. Fig. VI is a fragmentary horizontal sectional view taken on line VI in Fig. II. Fig. VII is a vertical fragmentary sectional view taken on the line VII, VII in Fig. I. Fig. VIII is an elevation of a 95 modified form of my invention, having a water supply pipe permanently connecting the water receptacle thereof with the radiator water supply of an automobile; such water supply to the generator being controlled by a manually operative valve. Fig. IX is a plan view of the form of my invention shown in Fig. VIII. Fig. X is a vertical sectional view of said generator taken on the line X, X in Fig. IX. Fig. XI is a 100 sectional view of the water receptacle shown in Fig. X, but taken on the line XI, XI in Fig. IX; portions of said receptacle being shown in elevation. Fig. XII is a vertical fragmentary sectional view in the 105 same plane as Fig. VII but showing the base portion of the generator.

Referring to the form of my invention shown in Figs. I to VII inclusive, the generator has the base 1 including the condensate trap 2 cast in unitary relation with the feet 3 having the openings 4 by which it may be permanently connected with an automobile or other vehicle. Said trap has a gas inlet 6 at the top thereof and a condensate outlet 7 at the bottom thereof and two eccentric sockets 8 at the bottom thereof, shown in Fig. I. The two branch condensing coils 10 and 11 which are carried by said base 1, to which they are detachably secured by the bolt 13 and yokes 14 and 15, have means including the nuts 16 detachably connecting said coils in communication with said trap 2 by way of ducts 18 and 19. It is to be understood that the moisture entrained in the gas passing from said inlet 6 and through the trap 2 and said coils 10 and 11 is condensed and the condensate gravitates to the bottom of said trap 2 as indicated at 20 in Fig. II.

The carbid casing 22, having the central tubular column 23 and the gas outlet 24 at the bottom thereof, is reinforced by the spider frame 25, which is conveniently riveted thereon as indicated at 26 in Fig. II, and is detachably fitted to said base 1; the latter having the resilient gasket 28 surrounding said gas inlet 6 and retained by the ring 29 held by the screw 30 engaging said base 1, as shown in Fig. II, so as to seal the joint between said gas outlet 24 of the carbid casing 22 and the gas inlet 6 of the generator base 1. It is to be understood that the gas passes upwardly in the carbid chamber both between the flanges 34 and 35 and between the columns 23 and 41 and thence downwardly through the column 23 and the gas outlets 24 and thence through the gas inlet 6 of the trap; the interstices between said column 23 and the stem 125 and the fittings on the latter being ample to permit such passage.

The carbid 32 is supported in said carbid casing 22 in the removable basket 33 having its annular top flange 34 resting upon the annular top flange 35 of said carbid casing 22, and said basket has the foraminous bottom 37, conveniently formed of wire fabric held by the annular flange 38 and having a central aperture, fitted to said carbid casing column 23, reinforced by the ring 39 which is soldered to said fabric. The carbid 32 is retained in said basket 33 by the removable cap 40 which fits therein as shown in Fig. II and has the central tubular column 41 which fits over said column 23 of the carbid casing. The downward movement of said cap 40 in said basket 33 is limited by three stop lugs 42 which are stationary in said basket and one of which is shown on the left hand side of Fig. II. Said cap 45 is held in said basket and prevented from

rattling by the spiral spring 45, the lower end of which is connected with said cap, by solder, and the upper end of which bears upon the foraminous floor 46 of the gas dome 47 which extends into the water receptacle 48 and forms part of the bottom of the latter. Said water receptacle 48 is arranged to detachably fit upon said carbid casing 22, and has the resilient gasket 50 held between its bottom flanges 51 and 52 resting upon said top flange 35 of the carbid casing 22 so as to seal the joint between said carbid casing and said water receptacle 48. Said water receptacle has the central tubular column 54 in axial alignment with the column 23 in said carbid casing, and includes the main compartment 56, adjacent said casing, and the auxiliary compartment 57 above said main compartment, said compartments being separated by the diaphragm 58.

The valve casing 60 which is permanently set in the bottom of said main compartment 56 of the water receptacle has the water inlet passageway 61 leading to the restricted water outlet 62 in the bottom of said valve casing and to the similar restricted water outlets 63 in fittings 64 which are also permanently set in the bottom of said compartment 56 as indicated in Fig. IV and connected with said valve casing 60 by the branch tubes 66. Each of said water outlets 52 and 63 is conveniently provided with a reciprocatory plunger 68 such as shown in Fig. II, arranged to restrict the flow of water and to be longitudinally shifted to free any obstruction which may lodge in said outlets. It is to be understood that when said passageway 61 is in communication with said outlets 62 and 63 water is permitted to drip through said outlets upon the rounded top of the cap 40 and flows down the latter between its vertical wall and the vertical wall of the basket 33 and is distributed circumferentially thereon by the bead 70 from which it flows in a thin film to the carbid 32. Said water passageway 61 is controlled by the valve plug 72 which is mounted to turn in said valve casing 60 to the degree limited by the stud 73 on said plug encountering the shoulders 74 and 75 on said casing, which are shown in Fig. IV. Said valve plug 72 is provided with a stem 77 extending through the tube 78 which is permanently secured in said diaphragm 58 and in the top of the water receptacle 48 and is provided above the latter with the operating handle 79 which is detachably secured thereon by the screw 80. It may be observed, with reference to Fig. II, that said handle 79 has a flange 81 overhanging the top of said tube 78 and the joint between them is sealed by the resilient gasket 82. As best shown in Fig. III, said valve stem 77 also carries the valve 84 which has a face

of resilient material 85 (for instance leather) bearing upon the inner face of said tube 78 toward which said valve 84 is pressed by the springs 86 which surround the studs 87 extending through said valve stem 77. Said valve 84 is provided to control the water passageway 89 leading from said auxiliary water compartment 57 to the main water compartment 56, and it may be observed that the construction and arrangement is such that when the water passageway 61 from the main compartment to the carbid casing is closed, the water passageway 89 leading from said auxiliary compartment to said main compartment is opened as shown in Fig. II, and vice versa as shown in Fig. III. Moreover, I provide a gas passageway from said carbid casing 22 to the atmosphere, controlled by the same valve means, so that any gas generated after the water is shut off at said passageway 61 may escape directly to the atmosphere instead of through said condensing coils 10 and 11 to the lamps. Said passageway is shown at 91 in Fig. II, extending from the gas dome 47 through said valve casing 60 and the port 92 in said valve plug 72 and terminating in the gas vent nozzle 93 exterior to the water receptacle 48, and is closed when said plug is turned to open said passageway 61 as shown in Fig. III. Therefore, it may be observed that the generator above described includes a gas passageway from said carbid casing to the atmosphere; a water passageway leading from said main compartment of the water receptacle into said carbid casing; a water passageway from said auxiliary compartment in the water receptacle to said main compartment, and valve means controlling said gas and water passageways, so constructed and arranged that when the gas passageway is opened, the water passageway between said compartments is opened and the water passageway from said main compartment to said carbid casing is closed, and vice versa.

Referring to Figs. I, II, III and IV, it may be observed that the position of said valve means and consequent operative or inoperative condition of the generator is manifested by the position of the exterior operating handle 79, which in Figs. I, II and IV is in the position to shut off the supply of water from the water receptacle to the carbid casing, as indicated by said handle registering with the sign "Off" which is cast in unitary relation with the spider frame 95 which is permanently set in the top of the water receptacle shown in Figs. I and II.

As shown in Figs. I and VII, the water receptacle 48 is provided with two inlets or filler tubes 97 and 98. Said tube 97 extends from the exterior of said receptacle 48 through the top thereof and through the

diaphragm 58 into the main water compartment 56 and is provided with the closure 100 which is eccentrically pivotally connected with said tube 97 by the pintle 101, which extends through the bearing 102 which is stationary in the receptacle 48. Said pintle carries at its lower end the abutment 103 for the spring 104 which encircles said pintle and tends to press said closure 100 shut, as shown in Fig. VII, but does not prevent ingress of air to said auxiliary water compartment 57, as the water is discharged from the latter into the carbid casing 22 through the outlets 62 and 63. It is to be understood that when it is desired to fill said main water compartment 56 in the water receptacle 48, said closure 100 may be raised by its knob 106 and turned aside to uncover said tube 97 to permit water to be poured therein, and when said closure is returned to registry with said tube 97 it is shut thereon by said spring 104. Said tube 98 extends from the exterior of said receptacle 48 through the top thereof to the auxiliary water compartment 57, and is provided with a closure 108 which is eccentrically pivotally connected with said tube 98 by the pintle 109 extending through the bearing 110, which is stationary in the receptacle 48. Said pintle carries at its lower end the abutment 112 for the spring 113 which encircles said pintle and tends to press said closure 108 shut, as shown in Fig. VII. It is to be understood that when it is desired to fill said auxiliary water compartment 57 in the water receptacle 48, said closure 108 may be raised by its knob 114 and turned aside to uncover said tube 98 to permit water to be poured therein, and when said closure is returned to registry with said tube 98 it is shut thereon by said spring 113. It may be observed, with reference to Figs. I and VII, that said knob 114 of the closure 108 has an opening 115 extending therethrough maintaining communication between the interior of said auxiliary water compartment 57 and the outer atmosphere so as to avoid the creation of a partial vacuum by the subsidence of the water 116 in the receptacle 48, which might interfere with the gravitational feed of the water to the carbid.

Means are provided for detachably rigidly connecting said carbid casing 22 and water receptacle 48 with said base 1, including the screw threaded rod 118 depending in said water receptacle column 54 from the top thereof, having the operating handle 119 provided with the resilient gasket 120 bearing upon the top of said spider frame 95 and sealing the joint thereof. As shown in Fig. II, said rod 118 has the annular flange 121 at its lower end preventing it from being withdrawn outwardly from said water receptacle 48, but permitting it to reciprocate longitudinally to a limited extent 130

sufficient to facilitate the engagement of the screw thread 123 at the lower end of said rod 118, with the screw thread 124 at the upper end of the stem 125 which extends in 5 the carbid casing column 23 from the base 1.

As shown in Fig. II, said stem 125 extends through said trap 2 and carries at its lower end the closure 127 for said condensate outlet 7; said closure 127 carrying 10 the resilient gasket 128 to seal said outlet when the connection between said rod 118 and stem 125, is tightened by rotation of said handle 119. In order to prevent rotation of said stem 125 when engaged by said 15 rod 118, said closure is provided with two eccentric studs 130 extending in said sockets 8 in the base 1, which hold the springs 131 pressing upon said closure 127 so as to automatically open the latter when said stem 20 125 is released by said rod 118.

The generator above described is operated as follows:—The generator being charged with carbid in the basket 33 and both compartments 56 and 57 charged with water, 25 and the valve handle 79 being turned to the position shown in Figs. I, II, IV, V and VI, the generator is in inoperative position because the water passageway 61 leading from the receptacle 48 to the carbid casing 22 is 30 closed and the gas passageway leading from the carbid casing 22 to the atmosphere is open, as shown in Fig. II. In this position, the water passageway 89, leading from the auxiliary water compartment 57 to the main 35 compartment 56 is open and, said auxiliary compartment being in communication with the atmosphere through the opening 115 in the knob 114 of the closure 108, the water 40 116 is free to subside into the main water compartment 56. It being desired to operate the generator, the valve handle 79 is turned from the position shown in Figs. I, II, IV, V and VI to the position shown in Fig. III, through an arc of 90 degrees, its 45 motion being limited by the circumferential length of the recess in the valve casing 60 in which the stud 73 extends as shown in Fig. IV. Thereupon, the water passageway 61, leading from the main water compartment 56 to the restricted outlets 62 and 63 being open, the water gravitates through 50 said outlets upon the cap 40 and thence to the carbid 32, decomposing the latter and generating gas which is forced by its own 55 pressure through the interstices between the gas inlet tube 6 of the base 1 and the stem 125 of the closure 127 into the trap 2 and thence through the ducts 18 and 19 to the condensing coils 10 and 11 and thence to the 60 lamps or other gas consuming devices connected to the upper end of said coils, conveniently by flexible rubber tubes. The ash residue 132 of the decomposition of the carbid 32 falls through the foraminous floor 37 65 of the carbid basket 33 to the bottom of the

carbid casing 22 as indicated in Fig. II, and the condensate from the gas gravitates to the bottom of the trap 2 as indicated at 20 in said figure.

If the operation of the generator is continued, without shutting off the water feed, (by returning the valve handle 79 to the initial position shown in Fig. I,) the water may be exhausted from the main compartment 56 to the level of the bottom of the 70 water passageway 61. However, during such operation, the gas pressure would gradually diminish because of the diminishing rate at which the water would gravitate through the outlets 62 and 63, consequent 75 upon the lessening height and consequent pressure of the water in the main compartment 56; and such diminution in pressure would be manifest by the lessening brilliance of the flames of the lamps. It may be observed that such diminishment in the gas 80 pressure is characteristic of all generators which have a single supply of water the pressure of which diminishes as the water is consumed in decomposing the carbid. However, with my improved construction above 85 described, the water pressure may be repeatedly restored to its original amount by momentarily returning the valve handle 79 to the "Off" position shown in Fig. I, thus 90 permitting the water from the auxiliary compartment 57 to recharge the main compartment 56 to its initial extent. Moreover, it may be observed that when the valve is in 95 said "Off" position, the water rises in the 100 column 78, so that when the valve handle 79 is turned to the position shown in Fig. III, which is the gas generating position, the initial pressure of the water is that incident to the height of the water in the main 105 compartment 56 plus the height of the water in the column 78; but the latter only holds a small quantity of water which quickly subsides to the level of the water in the lower main compartment 56, when the valve 84 is 110 closed as shown in Fig. III. The effect of such construction and arrangement is that each time the water is turned on to the carbid, it is initially fed to the latter at a rate much higher than the normal rate so as to 115 instantly generate sufficient gas to fill the gas spaces in the apparatus and provide sufficient gas pressure at the lamps to properly illuminate the latter. When it is desired to extinguish the lamps, the valve lever 120 79 is returned to the "Off" position, shown in Fig. I, so as to shut off the water, but the residue of water in the carbid 32 would continue the generation of gas at a gradually diminishing rate for perhaps several minutes, and the lamps would remain lighted if it were not that the gas passageway 91 is then opened to the atmosphere so that the gas escapes therethrough and the lamps are 125 then instantly extinguished.

It may be observed that whenever it is desired to recharge the generator with carbid 32, it is necessary to disconnect the rod 118 from the stem 125 by rotating said rod 5 by the handle 119 thus releasing said stem and, upon such release, the closure 127 is automatically opened by the springs 131 so as to automatically discharge the condensate from the trap 2. Consequently, it is impossible to have the generator obstructed 10 by accumulated condensate which might occur if such discharge were not thus automatically effected. Said rod 118 being disconnected, as above described, the water receptacle 48 may be lifted by the handle 119, the bottom flange 121 on said rod engaging the lower end of the column 54 of said receptacle. The cap 40 being thus released from the pressure of its spring 45, may be 15 removed from the carbid basket 33 and the latter removed from the carbid casing 22 and the latter may also be removed from the base 1 to facilitate the removal of the ashes 132 at the bottom of said casing. Said 20 casing 22 may then be replaced upon the base 1, and the basket 33 recharged with carbid being placed in said casing, covered with the cap 40, the water receptacle 48 may be replaced and said members connected in 25 rigid relation by rotation of the handle 119 until the closure 127 is returned to its closed position, shown in Fig. II. Thereupon, the generator is in condition to generate gas upon movement of the valve 30 handle 79 to the position shown in Fig. III, as above described.

Referring to the form of my invention shown in Figs. VIII to XI inclusive: the generator has the base 135 including the condensate trap 136 cast in unitary relation with the feet 137 having the openings 138 by which it may be permanently connected with an automobile or other vehicle. Said trap has the gas inlet 140 at the top thereof 45 and the condensate outlet 141 at the bottom thereof. The duct 144 leads from said trap 136, by way of the branch ducts 145 to respective branch condensing coils 146 and 147 through which the gas from the generator 50 is delivered to the lamps or other gas condensing devices which are connected therewith, conveniently by the flexible tubing 149. Said coils are carried by said base 135 to which they are detachably secured by the bolt 150 and yokes 151 and 152 and have means including the nuts 154 detachably connecting said coils in communication with said ducts 145. It is to be understood that the moisture entrained in the gas passing 55 from said inlet 140 and through the trap 136 and said coils 146 and 147 is condensed and the condensate gravitates to the bottom of said trap as indicated at 156 in Fig. X.

The carbid casing 158 has the central tubular column 159 with the gas outlet 160

at the bottom thereof, detachably secured therein by its screw thread 161 and the nut 162 and is detachably fitted to said base 135; the latter having the resilient gasket 164 surrounding said gas inlet 140 and retained 70 by the ring 165 held by the screw 166 engaging said base 135, as shown in Fig. X, so as to seal the joint between said gas outlet 160 of the carbid casing 158 and the gas inlet 140 of said generator base 135. The carbid 75 168 is supported in said carbid casing 158 in the removable cartridge 169 the shell of which is a folded web of textile fabric holding said carbid 168 equally distributed throughout its length in the separate compartments conveniently formed by parallel lines of stitches 171. Said textile fabric is of course flexible, and the arrangement is such that the separate compartments may be independently charged with carbid. 80 Said cartridge shell may be closed at the top, conveniently by the line of stitches 172 shown in Fig. X, or it may be left open at the top if it is desired to use the cartridge 169 repeatedly with successive charges of 90 carbid 168. In the latter case, the top of the cartridge being open permits the ejection of the carbid ash. However, the shell of said cartridge 169 being inexpensive textile fabric such as cheese cloth, it is preferable 95 to close the cartridges as shown in Fig. X, so as to prevent accidental escape of the carbid during the preliminary handling of the cartridges: the latter being thrown away when the carbid charge thereof is depleted. 100

In order to facilitate the absorption of water by the carbid 168 as the latter decomposes, I find it preferable to compress said cartridge 169 at the bottom of the carbid casing 158. In order to effect such compression, I provide the bowl 174 encircling the central column 159 in said casing 168 but removable therefrom, said bowl being provided with the spiral spring 175 which is permanently attached thereto at its lower 110 end. Such attachment is conveniently effected by the brackets 176 which are soldered to said bowl and spring so as to leave a space between them for the passage of water. The upper end of said spring 175 bears upon the 115 foraminous conical floor 177 of the dome 179 which extends into the water receptacle 180 and forms part of the bottom of the latter. Said water receptacle 180 is arranged to detachably fit upon said carbid casing 120 158, and has the resilient gasket 181 held between its bottom flange 182 and 183 resting upon the upper edge of said casing 158 so as to seal the joint between said casing and said water receptacle 180. Said water 125 receptacle 180 has the central tubular column 185 in axial alinement with the column 159 in said carbid casing, and includes the main compartment 187, adjacent said casing, and the auxiliary compartment 188 above 130

said main compartment, said compartments being separated by the diaphragm 189. The valve casing 191 which is permanently set in the bottom of said main compartment 187 of the water receptacle has the water inlet 5 passageway 195 leading to the restricted water outlet 196 in the bottom of said valve casing and to the similar restricted water outlets 197 in fittings 198 which are also permanently set in the bottom of said compartment 190 as indicated in Fig. XI and connected with said valve casing 194 by the branch tubes 200. Each of said water outlets 196 and 197 is conveniently provided 10 with a reciprocatory plunger 202 such as shown in Fig. X, arranged to restrict the flow of water and to be longitudinally shifted to free any obstruction which may lodge in said outlets. It is to be understood that when said passageway 195 is in communication with said outlets 196 and 197 water is permitted to drip through said outlets into said bowl 174 and thence, through the central opening at the bottom thereof encircling the column 159, and thence to the bottom of the casing 158; the rounded surface thereof serving to distribute the water radially into the textile fabric of the cartridge 169 through which it is absorbed into 25 contact with the carbid 168 in the several compartments thereof. Said water passageway 195 is controlled by the valve plug 209 which is mounted to turn in said valve casing 194 through an arc of 90 degrees, to 30 and from the position shown, such movement being limited by a stud on said plug encountering shoulders on said casing. Said valve plug 209 has the stem 211 extending through the tube 212, permanently 35 secured in said diaphragm 189 and in the top of the water receptacle 180, and has the operating handle 213 which is detachably secured thereon by the screw 214. Said handle 213 has the circular flange 215 over- 40 hanging the top of said tube 212 and the joint between them is sealed by the resilient gasket 216. Said valve stem 211 also carries the valve 218 which has a face of resilient material 219 (for instance leather) bearing upon the inner face of said tube 212 toward which said valve 218 is pressed by the 45 springs 220. Said valve 218 is provided to control the water passageway 223 leading from said auxiliary water compartment 188 to the main water compartment 187, and it 50 may be observed that the construction and arrangement is such that when the water passageway 195 from the main compartment to the carbid casing is closed, the water passageway 223 leading from said auxiliary compartment to said main compartment is 55 opened as shown in Fig. X, and vice versa. Moreover, I provide a gas passageway from 60 said carbid casing 158 to the atmosphere, controlled by the same valve means, so that

any gas generated after the water is shut off at said passageway 195 may escape directly to the atmosphere instead of through said condensing coils 146 and 147 to the lamps. Said passageway is shown at 225 70 in Fig. X, extending from the gas dome 179 through said valve casing 194 and the port 226 in said valve plug 209 and terminating in the gas vent nozzle 227 exterior to the water receptacle 182, and is closed when said 75 plug is turned to open said passageway 195. Therefore, it may be observed that the generator above described includes a gas passageway from said carbid casing to the atmosphere; a water passageway leading from 80 said main compartment of the water receptacle into said carbid casing; a water passageway from said auxiliary compartment in the water receptacle to said main compartment, and valve means controlling said 85 gas and water passageways, so constructed and arranged that when the gas passageway is opened, the water passageway between said compartments is opened and the water passageway from said main compartment 90 to said carbid casing is closed, and vice versa. It is to be understood, that the construction and arrangement above described 95 regulates and renders as uniform as possible the rate of flow of water into and through said bowl 174, and consequently insures the uniform supply of water to the several compartments of said cartridge 169, and the generation of gas therefrom.

As shown in Figs. X and XI, the water 100 receptacle 180 is provided with the reinforcing cap 229, which is permanently secured thereon, and has the inlet or filler tube 230 extending from the exterior of said receptacle 180 through the top thereof into the 105 auxiliary water compartment 188 and is provided with a closure 232 which is eccentrically pivotally connected with said tube 230 by the pintle 233 which extends through the bearing 234 and carries at its lower end 110 the abutment 235 for the spring 236 which encircles said pintle and tends to press said closure 232 shut. It is to be understood that when it is desired to fill said receptacle 180 with water, said closure 232 may be raised 115 by its knob 239 and turned aside to uncover said tube 230 to permit water to be poured therein, and when said closure is returned to registry with said tube 230, it is tightly shut thereon by said spring 236. However, 120 when said closure is opened, as aforesaid, and the valve 218 turned to the position shown in Fig. X, the water passageway 223 leading from said auxiliary compartment 188 to said main compartment 187 is open so that 125 both compartments of said receptacle may be filled with water 240 through the inlet 230.

In order to avoid the creation of a partial vacuum by subsidence of the water 240 in 130

the receptacle 180, which might interfere with the gravitational feed of the water to the carbid, I provide the top of the receptacle 180 with an aperture 242 in communication with the air vent 243 opening through said cap 229 in communication with the outer atmosphere. It may be observed that said aperture 242 and vent 243 are out of alignment, so that if any water is forced through the top of the receptacle 180 by back pressure of gas in the generator, it is caught in said cap 229 and subsequently gravitates back into the receptacle 180, instead of being thrown out of the generator as it would be if said aperture 242 communicated directly with the atmosphere.

In order to avoid the creation of a partial vacuum by subsidence of the water 240 in the main compartment 187 of the water receptacle 180 when the passageway 223 leading from the auxiliary water compartment 188 to said main water compartment 187 is closed by said valve 218; I provide the tube 244 (shown in Fig. XI) which maintains communication between said main compartment 187 and the interior of said cap and thence through the aperture 242 which is in communication with the outer atmosphere through said air vent 243. Means are provided for detachably rigidly connecting said carbid casing 158 and water receptacle 180 with said base 135, including the screw threaded rod 245 depending in said water receptacle column 185 from the top thereof, having the operating handle 246 provided with the resilient gasket 247 bearing upon the top of said cap 229 and sealing the joint thereat. Said rod 245 may be reciprocated longitudinally to facilitate the engagement of the screw thread 250 at the lower end thereof with the screw thread 251 at the upper end with the stem 252 which extends in the carbid casing column 159 from the base 135, and extends through said trap 136 and carries at its lower end the closure 254 for said condensate outlet 141. Said closure 254 carries the resilient gasket 255 to seal said outlet when the connection between said rod 245 and stem 252 is tightened by rotation of said handle 246. In order to prevent rotation of said stem 252 when engaged by said rod 245, said closure is provided with eccentric studs 259 extending in sockets 260 in said base 135 which hold spiral springs 261 pressing upon said closure 254 so as to automatically open the latter when said stem 252 is released by said rod 245, such construction being like that at the base of the other modification of my invention above described. Said water receptacle 180 is also conveniently provided with the water inlet 263 connected by the flexible water supply conduit 264 with the water circulating space in the radiator 265; so that said receptacle may be supplied with

water from said circulating system under control of the manually operative valve 266.

The generator last above described is operated as follows:—The generator being charged with carbid, in the cartridge 169, and the valve handle 213 being turned to the position shown in Figs. IX and X, the generator is in inoperative position because the water passageway 195 leading from the receptacle 180 to the carbid casing 158 is closed and the gas passageway leading from the carbid casing 158 to the atmosphere, through the valve plug 209, is open. In this position, the water passageway 223, leading from the auxiliary water compartment 188, to the main compartment 187 is open and, said auxiliary compartment being in communication with the atmosphere through the aperture 242 and vent 243, the water 240 is free to subside and entirely fill the main compartment 187. It being desired to operate the generator, the valve handle 213 is turned from the position shown in Figs. IX, X and XI, through an arc of 90 degrees. Thereupon, the water passageway 195 leading from the main water compartment 187 to the restricted outlets 196 and 197 being open, the water gravitates through said outlets upon the bowl 174 and thence to the carbid 168, decomposing the latter and generating gas which is forced by its own pressure upwardly through the central aperture in the conical floor 177 surrounding the column 159, thence between said columns 159 and 185 to the top of the column 159, thence downwardly between said column 159 and the rod 245 and through the interstices between the gas inlet tube 140 of the base 135 and the stem 252 of the closure 254 into the trap 136 and thence through the ducts 144 and 145 to the condensing coils 146 and 147 and thence to the lamps or other gas consuming devices connected to the upper ends of said coils, conveniently by flexible rubber tubes.

The ash residue of the decomposition of the carbid 168 is retained by the porous casting of the cartridge 169 so that it may be removed with the latter. The condensate 156 from the gas gravitates to the bottom of the trap as indicated and is automatically discharged therefrom whenever the closure 254 is opened by release of the stem 252.

If the operation of the generator is continued, without shutting off the water feed, (by returning the valve handle 213 to the initial position shown in Figs. IX, X and XI.) the water may be exhausted from the main compartment 187 to the level of the bottom of the water passageway 195. However, during such operation, the gas pressure gradually diminishes because of the diminishing rate at which the water gravitates through the outlets 196 and 197, consequent upon the lessening height and consequent

pressure of the water in the main compartment 187; and such diminution in pressure may be manifested by the lessening brilliancy of the flames of the lamps. It may be observed that such diminishment in the gas pressure is characteristic of all generators which have a single supply of water the pressure of which diminishes as the water is consumed in decomposing the carbid. However, with my improved construction above described, the water pressure may be repeatedly restored to its original amount by momentarily returning the valve handle 213 to the "Off" position shown in Fig. IX, thus permitting the water from the auxiliary compartment 188 to recharge the main compartment 187 to its initial full extent. Moreover, it may be observed that when the valve is in said position the water rises in the tube 212 to the level of the water in the upper auxiliary compartment 188, so that when the valve handle 213 is turned to the other position, which is the gas generating position, the initial pressure of the water is that incident to the height of the water in the main compartment 187 plus the height of the water in said tubes 212 and 245; but said tubes only hold a small quantity of water which quickly subsides to the level of the water in the lower compartment 187 when the valve 218 is thus closed. The effect of such construction and arrangement is that each time the water is turned on to the carbid, it is initially fed to the latter at a rate much higher than the normal rate so as to instantly generate sufficient gas to fill the gas spaces in the apparatus and provide sufficient gas pressure at the lamps to properly illuminate the latter.

When it is desired to extinguish the lamps, the valve lever 213 is turned to the position shown in Fig. IX, so as to shut off the supply of water to the carbid casing 158, but the residue of water in the cartridge 169 continues the generation of gas at a gradually diminishing rate for perhaps several minutes and the lamps would remain lighted if it were not that the gas passageway 225 is then opened to the atmosphere so that the gas escapes therethrough and the lamps are instantly extinguished.

It may be observed that whenever it is desired to recharge the generator with carbid 168, it is necessary to disconnect the rod 245 from the stem 252 by rotating said rod by its handle 246 thus releasing said stem 252 and, upon such release, the closure 254 is automatically opened by the springs 261 so as to automatically discharge the condensate 156 from the trap 136. Consequently, it is impossible to have the generator obstructed by accumulated condensate which might occur if such discharge were not thus automatically effected. Said rod 245 being disconnected, as above described,

the water receptacle 180 may be lifted from the carbid receptacle 158 thus releasing the spring 175 of the bowl 174 so that the latter may be removed to permit removal of the depleted cartridge 169. The ash residue 70 of the decomposed carbid 168 being retained by the cartridge 169, it is unnecessary to clean the carbid casing 158 before recharging it with carbid, and such recharging may therefore, be immediately effected by disposing another cartridge annularly in the carbid casing as indicated in Fig. XI. Said bowl 174 may then be replaced, and the spring 175 compressed by replacing the water receptacle 180, so as to compress the 80 carbid in the cartridge, and the various separable members of the generator aforesaid be reconnected in rigid relation by rotation of said handle 246 until the closure 254 is returned to its closed position shown 85 in Fig. X. Thereupon, the generator is in condition to generate gas upon movement of the valve handle 213 from the position shown in Figs. IX, X and XI, through an arc of 90 degrees as above described.

It is to be particularly noted that the central tubular column 159 of the carbid casing 158 extends far above the latter and is imperforate; because such construction compels the gas generated in said casing 158 to pass in a thin film between the central tubular column 185 of the water receptacle and said column 159, to the top of the latter, and to pass downward in a film between said column 159 and the rod 245. Said gas 100 is thus subjected to the low temperature maintained by the water surrounding said column 185 so as to precipitate the greater portion of the condensate therefrom in position to return into operative relation with 105 the carbid 168 by trickling down the outer surface of said column 159. Such construction is not only advantageous in that it insures the separation of the entrained moisture from the gas but retains the bulk of 110 such moisture in operative relation with the carbid and thus permits the generation of a larger volume of gas from a given charge of water than if the condensate were permitted to escape from the generator. In 115 order to insure that said water inlet or filler tube 230 shall not be opened when the generator is in operative position; I provide said valve handle 213 with the locking flange 268, best shown in Fig. IX, which 120 overhangs the closure 232 and prevents the latter from being raised when said handle 213 is turned to the position in which water is being supplied to the carbid and gas generated.

It is to be understood that I do not desire to limit myself to the precise details of construction and arrangement above described, as it is obvious that various modifications may be made therein without depart- 130

ing from the essential features of my invention, as defined in the following claims.

I claim:—

1. In an acetylene gas generator, the combination with a base, of a carbid casing, having a central tubular column and a gas outlet at the bottom thereof, detachably fitted to said base; a water receptacle having a central tubular column and arranged to detachably fit upon said carbid casing with said columns in registry, above said carbid casing, including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment; a passageway from said auxiliary compartment to said cap; a passageway from said main compartment to said cap; a vent opening from said cap to the atmosphere; a gas passageway from said carbid casing to the atmosphere; and a rotary valve controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle with said base, including a screw threaded rod depending in said water receptacle column from the top thereof, and a screw threaded stem extending in said carbid casing column from said base, in screw threaded engagement with said rod; said stem extending through said trap in said base and carrying at its lower end a closure for said condensate outlet; a handle on said rod above said water receptacle; and resilient means arranged to automatically open said closure whenever said stem is released by rotation of said rod.
2. In an acetylene gas generator, the combination with a base, of a carbid casing, having a central tubular column and a gas outlet at the bottom thereof, detachably fitted to said base; a water receptacle having a central tubular column and arranged to detachably fit upon said carbid casing with said columns in registry, above said carbid casing, including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment; a passageway from said auxiliary compartment to said cap; a passageway from said main compartment to said cap; a vent opening from said cap to the atmosphere; a gas passageway from said carbid casing to the atmosphere; and a rotary valve controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle.

from said cap to the atmosphere; a gas passageway from said carbid casing to the atmosphere; valve means controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle with said base, including a screw threaded rod depending in said water receptacle column from the top thereof, and a screw threaded stem extending in said carbid casing column from said base, in screw threaded engagement with said rod; said stem extending through said trap in said base and carrying at its lower end a closure for said condensate outlet; a handle on said rod above said water receptacle; and resilient means arranged to automatically open said closure whenever said stem is released by rotation of said rod.

3. In an acetylene gas generator, the combination with a carbid casing, having a central tubular column and a gas outlet at the bottom thereof; a water receptacle having a central tubular column and arranged to detachably fit upon said carbid casing with said columns in registry, including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment to said carbid casing; a water passageway from said auxiliary compartment to said cap; a passageway from said main compartment to said cap; a vent opening from said cap to the atmosphere; a gas passageway from said carbid casing to the atmosphere; and a rotary valve controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle.
4. In an acetylene gas generator, the combination with a carbid casing, having a gas outlet at the bottom thereof; a water receptacle above said carbid casing including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment; a passageway from said auxiliary compartment to said cap; a passageway from said main compartment to said cap; a vent opening to said carbid casing; a gas passageway from said carbid casing; and a water passageway from said main compartment to said carbid casing.

from said auxiliary compartment to said main compartment; a passageway from said auxiliary compartment to said cap; a passageway from said main compartment to said cap; a vent opening from said cap to the atmosphere; a gas passageway from said carbid casing to the atmosphere; and a rotary valve controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle.

5. In an acetylene gas generator, the combination with a carbid casing having a gas outlet; of a water receptacle above said carbid casing, including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment; a passageway from said auxiliary compartment to said cap; a passageway from said main compartment to said cap; a vent opening from said cap to the atmosphere; valve means controlling both of said water passageways, so constructed and arranged that when the water passageway between said compartments is opened the water passageway from said main compartment to said carbid casing is closed and vice versa; and means arranged to detachably connect said casing and receptacle.

6. In an acetylene gas generator, the combination with a carbid casing; of a water receptacle above said carbid casing, including a main compartment adjacent said carbid casing, an auxiliary compartment above said main compartment, and a hollow cap above said auxiliary compartment; a passageway from said main compartment to said cap; a water passageway from said main compartment to said carbid casing; a water passageway from said auxiliary compartment to said main compartment; a passageway from said auxiliary compartment to said cap; a vent opening from said cap to the atmosphere; valve means controlling both of said water passageways, so constructed and arranged that when the water passageway between said compartments is opened the water passageway from said main compartment to said carbid casing is closed and vice versa; and means arranged to detachably connect said casing and receptacle.

7. In an acetylene gas generator, the combination with a carbid casing; of a water

receptacle above said carbid casing, including a main compartment adjacent said carbid casing, an auxiliary compartment above said main compartment, and a hollow cap above said auxiliary compartment; a water passageway from said main compartment to said carbid casing; a passageway from said auxiliary compartment to said cap; a water passageway from said auxiliary compartment to said main compartment; a passageway from said main compartment to said cap; a vent opening from said cap to the atmosphere; valve means controlling both of said water passageways, so constructed and arranged that when the water passageway between said compartments is opened the water passageway from said main compartment to said carbid casing is closed and vice versa; and means arranged to detachably connect said casing and receptacle.

8. In an acetylene gas generator, the combination with a carbid casing; of a water receptacle arranged to detachably fit upon said carbid casing, including a main compartment adjacent said carbid casing and an auxiliary compartment above said main compartment; an air vent for said main compartment; a water passageway from said main compartment to said carbid casing; a water passageway from said auxiliary compartment to said main compartment; a gas passageway from said carbid casing to the atmosphere; valve means controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle.

9. In an acetylene gas generator, the combination with a carbid casing; of a water receptacle above said carbid casing including a main compartment adjacent said carbid casing and an auxiliary compartment above said main compartment; an air vent for said main compartment; a gas passageway from said carbid casing to the atmosphere; a water passageway from said main compartment to said carbid casing; a water passageway from said auxiliary compartment to said main compartment; and valve means controlling said gas passageway and both of said water passageways, so constructed and arranged that when the gas passageway is opened the water passageway between said compartments is opened and the water passageway from said main compartment to said carbid casing is closed, and vice versa.

10. In an acetylene gas generator, the combination with a carbid casing; of a water receptacle including a main compart-

combination with a carbid casing; of a water receptacle including a main compartment and an auxiliary compartment, and having a water inlet; a removable closure for said inlet; a gas passageway from said carbid casing to the atmosphere; a water passageway from said main compartment to said carbid casing; a water passageway from said auxiliary compartment to said main compartment; valve means controlling said gas passageway and both of said water passageways and carrying means arranged to prevent and permit the opening of said water inlet closure, so constructed and arranged that when the gas passageway is opened the water passageway between said compartments is opened and the water passageway from said main compartment to said carbid casing is closed and said water inlet closure is released, and, when the gas passageway is closed the water passageway between said compartments is closed and the water passageway from said main compartment to said carbid casing is opened, and said water inlet closure is prevented from opening; whereby, when water is being supplied to the carbid the escape of gas from the carbid chamber, otherwise than at the burners, is prevented, and, when the water supply to the carbid is shut off, a gas vent from the carbid chamber is provided independently of the burners.

17. In an acetylene gas generator, the combination with a carbid casing; of a water receptacle including a main compartment and an auxiliary compartment, and having a water inlet; a removable closure for said inlet; a water passageway from said main compartment to said carbid casing; a water passageway from said auxiliary compartment to said main compartment; valve means including a rotary plug controlling both of said water passageways and carrying means arranged to prevent and permit the opening of said water inlet closure, so constructed and arranged that when the water passageway between said compartments is opened the water passageway from said main compartment to said carbid casing is closed and said water inlet closure is released, and, when the water passageway between said compartments is closed the water passageway from said main compartment to said carbid casing is opened, and said water inlet closure is prevented from opening; whereby, when water is being supplied to the carbid the escape of gas from the carbid chamber, otherwise than at the burners, is prevented, and, when the water supply to the carbid is shut off, a gas vent from the carbid chamber is provided independently of the burners.

18. In an acetylene gas generator, the combination with a carbid casing; of a water receptacle including a main compartment

and an auxiliary compartment, and having a water inlet; a removable closure for said inlet; a water passageway from said main compartment to said carbid casing; a water passageway from said auxiliary compartment to said main compartment; valve means controlling both of said water passageways and carrying means arranged to prevent and permit the opening of said water inlet closure, so constructed and arranged that when the water passageway between said compartments is opened the water passageway from said main compartment to said carbid casing is closed and said water inlet closure is released, and, when the water passageway between said compartments is closed the water passageway from said main compartment to said carbid casing is opened, and said water inlet closure is prevented from opening; whereby, when water is being supplied to the carbid the escape of gas from the carbid chamber, otherwise than at the burners, is prevented, and, when the water supply to the carbid is shut off, a gas vent from the carbid chamber is provided independently of the burners.

19. In an acetylene gas generator, the combination with a carbid casing; of a water receptacle including a plurality of compartments, and having a water inlet; a removable closure for said inlet; water passageways between said compartments and between said receptacle and casing; valve means controlling said passageways and operatively connected with means arranged to prevent and permit the opening of said water inlet closure, so constructed and arranged that when the water passageway between said receptacle and casing is closed the passageway between the compartment local to said inlet and the adjacent compartment is opened and said water closure is released, and, when the water passageway from said receptacle to said casing is opened, said other water passageway is closed, and said water inlet closure is prevented from opening; whereby, when water is being supplied to the carbid the escape of gas from the carbid chamber, otherwise than at the burners, is prevented, and, when the water supply to the carbid is shut off, a gas vent from the carbid chamber is provided independently of the burners.

20. In an acetylene gas generator, the combination with a carbid casing; of a water receptacle having a water inlet; a removable closure for said inlet; a water passageway between said receptacle and casing; valve means controlling said passageway and operatively connected with means arranged to prevent and permit the opening of said water inlet closure, so constructed and arranged that when the water passageway between said receptacle and casing is closed said water closure is re-

leased, and, when the water passageway from said receptacle to said casing is opened, said water inlet closure is prevented from opening; whereby, when water is being supplied to the carbid the escape of gas from the carbid chamber, otherwise than at the burners, is prevented, and, when the water supply to the carbid is shut off, a gas vent from the carbid chamber is provided independently of the burners.

21. In an acetylene gas generator, the combination with a base; of a carbid casing, having a central tubular column and a gas outlet at the bottom thereof, detachably fitted to said base; a water receptacle having a central tubular column and arranged to detachably fit upon said carbid casing with said columns in registry, above said carbid casing, including a main compartment adjacent said carbid casing, an auxiliary compartment above said main compartment, and a hollow cap above said auxiliary compartment; a water passageway from said main compartment to said carbid casing; a water passageway from said auxiliary compartment to said main compartment; a passageway from said auxiliary

compartment to said cap; a passageway from said main compartment to said cap; a vent opening from said cap to the atmosphere; a gas passageway from said carbid casing to the atmosphere; and a rotary valve controlling said gas passageway and both of said water passageways, so constructed and arranged that when the gas passageway is opened the water passageway between said compartments is opened and the water passageway from said main compartment to said carbid casing is closed and vice versa; and means arranged to detachably rigidly connect said casing and receptacle with said base, including a screw threaded rod depending in said water receptacle column from the top thereof, and a screw threaded stem extending in said carbid casing column from said base, in screw threaded engagement with said rod.

In testimony whereof, I have hereunto signed my name at Philadelphia, Pennsylvania, this tenth day of September, 1913.

EDWIN M. ROSENBLUTH.

Witnesses:

E. G. McCULLOUGH,

Copies of this patent may be obtained for five cents each, by addressing the "Commissioner of Patents, Washington, D. C."

It is hereby certified that in Letters Patent No. 1,173,122, granted February 22, 1916, upon the application of Edwin M. Rosenbluth, of Philadelphia, Pennsylvania, for an improvement in "Acetylene-Gas Generators," errors appear in the printed specification requiring correction as follows: Page 2, line 98, for the reference-numeral "52" read 62; same page, line 112, for the word "bv" read *by*; page 9, line 5, claim 1, and line 48, claim 2, after the word "base" strike out the comma and insert a semicolon; and that the said Letters Patent should be read with these corrections therein that the same may conform to the record of the case in the Patent Office.

Signed and sealed this 16th day of January, A. D., 1917.

[SEAL.]

F. W. H. CLAY,
Acting Commissioner of Patents.

Cl. 48—4.
